UNITED STATES PATENT OFFICE

142,455

DESIGN FOR AN AUTOMOBILE

Edward C. Wells, Donald J. Euler, and Norbert A. Collins, near Seattle, Wash., assignors to Boeing Aircraft Company, Seattle, Wash., a corporation of Washington

Application August 9, 1944, Serial No. 114,795

Term of patent 14 years

(Cl. D14—3)

To all whom it may concern:

Be it known that we, Edward C. Wells, Donald J. Euler, and Norbert A. Collins, citizens of the United States of America, residing at or near Seattle, in the county of King and State of Washington, have invented a new, original, and ornamental Design for an Automobile, of which the following is a specification, reference being had to the accompanying drawing, forming part thereof.

Figure 1 is a side elevational view of an automobile, showing our new design;

Figure 2 is a front elevational view;
Figure 3 is a rear elevational view;
Figure 4 is a top plan view; and
Fig. 5 is a side perspective view thereof.
We claim:
The ornamental design for an automobile, substantially as shown.

EDWARD C. WELLS.
DONALD J. EULER.
NORBERT A. COLLINS.
